UNITED STATES PATENT OFFICE.

CLARENCE L. TAYLOR, OF ALLIANCE, OHIO, ASSIGNOR TO THE MORGAN
ENGINEERING COMPANY, OF ALLIANCE, OHIO.

OVERHEAD TRAVELING CRANE.

No. 821,136.

Specification of Letters Patent.

Patented May 22, 1906.

Application filed February 6, 1906. Serial No. 299,795.

To all whom it may concern:

drums 11, arranged with their axes in line 55

travel-motor and its shaft are located outside the path of travel of the chains on the main and auxiliary trolleys. Again, by dividing the main girder into two separated sections 5 for the passage between them of the hoisting-chains the weight is borne in a plane passing between such separated sections, thus obviating to a large extent the tendency of the long girders to spread under the weight of a 10 heavy load.

It is evident that changes in the details might be resorted to without departing from the spirit and scope of my invention. Hence 15 I would have it understood that I do not confine myself to the exact details shown and described, but consider myself at liberty to make such changes as fairly fall within the spirit and scope of my invention.

Having fully described my invention, what 20 I claim as new, and desire to secure by Letters Patent, is—

1. In an overhead crane, the combination of two main girders each made up of two parallel separated sections, the latter being 25 connected from end to end, a trolley having bearing on each section of said main girders, intermediate girders and a trolley mounted on said intermediate girders.

2. In an overhead crane, the combination of two main girders each composed of two parallel separated sections, the sections comprising each main girder being disconnected from end to end, a trolley having bearing on each section of said main girders and carrying 35 hoisting-chains which pass between said sections, intermediate girders and a trolley mounted on said intermediate girders, the chains from said latter trolley passing between the intermediate girders.

40 3. In an overhead crane, the combination with two girders each composed of two parallel separated sections, the sections comprising each girder being disconnected from end to end, and a trolley having bearing on each 45 section of said girders, of a trackway secured

to the inner sections of said girders, but below the plane of the top of the latter and an auxiliary trolley mounted on said trackway.

4. In an overhead crane, the combination with two main girders each composed of two parallel separated sections, the sections comprising each girder being disconnected from end to end and a trolley having bearing on each section of said girders, the hoist-chains of said trolley passing down between the sections of each girder, of a trackway secured to the inner section of said girders but below the plane of the top of the latter and auxiliary trolley on said trackway, the hoist-chain of said auxiliary trolley depending between 55 the rails of said trackway.

5. In an overhead crane, the combination with two main girders each made up of two parallel separated sections the latter being disconnected from end to end, of a trolley having bearing on each of said main sections and carrying hoisting-chains which pass downwardly between the sections of each girder.

6. In an overhead crane the combination 70 with two main girders each made up of two separated sections the latter being disconnected from end to end, of a trolley mounted on pivoted trucks, the wheels of the trucks at one side of the trolley resting and moving 75 on the separated sections of one girder and the wheels of the trucks at the other side of the trolley resting and moving on the separated sections of the other girder, and hoisting-chains carried by the trolley and passing 80 downwardly between the sections of the two girders.

In testimony whereof I have signed this specification in the presence of two subscribing witnesses.

CLARENCE L. TAYLOR.
